UNITED STATES PATENT OFFICE.

DANIEL R. WILL, OF AVA, ILLINOIS.

RAIL-FASTENER AND COMBINED METAL AND CEMENT TIE.

1,005,390.

Specification of Letters Patent. Patented Oct. 10, 1911.

Application filed July 8, 1911. Serial No. 637,560.

To all whom it may concern:

Be it known that I, DANIEL R. WILL, a citizen of the United States, residing at Ava, in the county of Jackson and State of Illinois, have invented a new and useful Rail-Fastener and Combined Metal and Cement Tie; and I do hereby declare the following to be a full, clear, and exact description of the invention, such as will enable others skilled in the art to which it appertains to make and use the same.

This invention relates to a new and useful rail fastener adapted principally in connection with the railway tie, shown, described and claimed in the Patent No. 955,928, dated April 26, 1910.

The principal object of the invention is the production of a rail fastener, the parts of which may be adjusted for clamping various sizes of rails.

A further feature of the invention is the fact that the bolts which secure the clamping plates to the tie, penetrate sleeves, which are embedded in the cement of the tie, as shown in the drawings.

A further feature of the invention is the provision of clamping plates having strengthening ribs, which merge together and terminate into shoulders, acting as abutments for the edges of transverse flat bars, through the ends of which the bolts, which fasten the clamping plates in position, penetrate.

The invention comprises further features and combination of parts, as hereinafter set forth, shown in the drawings and claimed.

In the drawings:—Figure 1 is a view in perspective of the improved rail fastener, as applied to a cement and metal tie, of the construction shown in the said patent. Fig. 2 is a sectional view, on line 2—2 of Fig. 1. Fig. 3 is a plan view showing the rail fastener as holding a rail of the largest size. Fig. 4 is a view of one of the clamping plates of the fastener removed, with the lowered clamping plate disposed therebeneath.

Referring to the drawings 1 designates a combined metal and cement tie, the same being constructed in accordance with the tie disclosed in the said Patent No. 955,928. Arranged adjacent the tie is a plate 2, having at each end on its upper face transverse corrugations 3, with which the corrugation 4 of the clamping plates 5 coöperate in order to prevent movement of the plates 5. These plates are recessed as shown at 6 to engage

the base of the rail, as shown in Figs. 1 and 2. The plates 5 are provided with slots 7, through which the bolts 8 extend. These bolts 8 also extend through the plate 2, into the sleeves 9 rectangular in cross section (which are embedded in the cement of the tie.) The bolts not only penetrate the sleeves, but also the bars 11 of the tie. The bolts, however, are first extended through the flat metal bars 12, which are disposed adjacent the upper faces of the plates 5. The ends of the bars 12 are turned upwardly after the bolts are inserted, as shown at 13, to contact with the bolt heads, to prevent the bolts from unscrewing.

The upper faces of the plates 5 are provided with a plurality of strengthening ribs 15, which merge together as shown at 16, in order to provide the shoulder 17, against which the upturned flanges of the bars 12 contact, that is, when the plates 5 are clamping a rail of the largest size as shown in Fig. 3.

To prevent end wise movement of the rail, the base flanges of each rail are slotted transversely thereof, as shown at 19, for the reception of the keys 20, which also engage the slots 21 of the plates 5, and the recess 22 of the plate 2.

From the foregoing it will be noted, that there has been produced a novel and simple rail fastener, adapted for use in connection upon combined metal and cement ties, and one which may be adjusted, for clamping various sizes of rails.

The invention having been set forth, what is claimed as new and useful is:—

1. In combination, a combined metal and cement tie, a plate having corrugations at each end arranged thereon, a rail resting on the plate, clamping plates, one upon each side of the rail engaging the base flanges thereof, the clamping plates having slots and provided with strengthening ribs merging into a shoulder, bolts penetrating the clamping plates and the first plate and anchored in the tie, bars through which the bolts extend having up turned flanges to engage the shoulder.

2. In combination, a combined metal and cement tie, a plate having corrugations at each end arranged thereon, a rail resting on the plate, clamping plates one upon each side of the rail engaging the base flanges thereof, the clamping plates having slots and provided with strengthening ribs merg-

ing into a shoulder, bolts penetrating the clamping plates and the first plate and anchored in the tie, bars through which the bolts extend having upturned flanges to engage the shoulder, and means penetrating the clamping plates and the rail for preventing endwise movement of the rail.

3. In combination, a combined metal and cement tie having sleeves embedded therein,
10 a base plate resting on the tie having corrugations at each end upon its upper face, a tie resting on the base plate, clamping plates having slots and provided with corrugations to engage the corrugations of the base plate,
15 one clamping plate being arranged on each side of the rail, the clamping plates having shoulders, metallic bars extending trans-

versely of the clamping plates and provided with upturned flanges to engage the shoulders, bolts penetrating the metallic bars, the 20 clamping plates, the base plate, and extending into the tie and anchored in the sleeves, the metal bars having upturned ends to engage the bolts, and a key penetrating the rail the clamping plate and the base plate 25 to prevent endwise movement of the rail.

In testimony whereof I have signed my name to this specification in the presence of two subscribing witnesses.

DANIEL R. WI
